DEVICE FOR GAUGING AND SAMPLING LIQUIDS IN CLOSED CONTAINERS

Harrison Otis Parsons, Houston, Tex.

Application October 23, 1937, Serial No. 170,555

7 Claims. (CL. 73—298)

This invention relates to a combination level gauge and sampling device for liquids in a container, and particularly to a device by means of which liquid levels in a closed container, maintained under pressure, ranging from sub-atmospheric to super-atmospheric in degree, may be obtained without undue variation of the conditions existing therein. The device may also be used to obtain samples of liquid from a container under super-atmospheric pressure, without danger of the uncontrolled release of the pressure in the container or of the contents thereof.

The invention and its scope may be fully understood from the following description, read in conjunction with the accompanying drawings, in which the same numerals are used to identify similar parts.

Fig. 1 is a detail side elevation of the device, with parts broken away.

Fig. 2 is a side elevation with parts broken away showing the details of the seals between the gauge tube and its housing.

Fig. 3 is an enlarged view of the lower end of the gauge tube, with parts broken away and showing the inlet valve for liquid in a closed position.

Fig. 4 is an enlarged view of the lower end of the gauge tube, with parts broken away and showing the inlet valve for liquid in an open position.

Fig. 5 is a vertical sectional view through a tank car at the dome, showing one application of the device.

Fig. 6 is a vertical end sectional view through an underground storage tank showing another application of the device.

Referring now to the drawings in Fig. 1 thereof, there is illustrated a device according to this invention in which numeral 1 designates a tubular housing formed of sections 2 and 3 joined as by a collar 4 with their ends separated by a packing gland 5. The housing 1 carries at its lower end a sleeve 6 having lateral openings 7 therein. A plug 8 having a groove 9 in its inner face, for a purpose later to be described, is threaded into the open end of the sleeve 6. A collar 10 is disposed on the upper end of said housing and carries a stuffing box member 11 adapted to receive a vapor cap 12. The cap 12 and plug 8 are preferably adapted for threaded engagement with the stuffing box member 11 and the sleeve 6 respectively and may be provided for the engagement of a wrench as at 13 and 14. A vent opening 16 is provided in that portion

of the housing which may be disposed within a container and below the packing gland 5.

Contained within the housing assembly described above and carried thereby, is the gauging and sampling assembly of the device indicated by the numeral 17. As illustrated, the assembly comprises a tubular casing formed by a top section 18, a gauge section 19, an intermediate section 20 and a bottom section 21, as well as those elements associated therewith and described in detail below. Of course the sections may be lengthened or increased in number without interfering in any manner with the operation of the device.

The respective sections are joined by means of couplings which provide a substantially smooth outer surface for the casing of the assembly 17 and permit sliding movement thereof through the packing gland 5 carried by the housing 1.

In the form illustrated, the gauge section 19 is joined to the top section 18 and to the intermediate section 20 by means of couplings 22 and 23 having exteriorly threaded ends, adapted for engagement interiorly of the respective sections, and annular flange 24 of a width

substantially equal to the wall thickness of the sections. In addition, couplings 22 and 23 cooperate with annular members 25 and 26 and compressible packing rings 27 to provide packing glands supporting a gauge glass 28 in fluid tight relation with the gauge section 19, which section is provided with a slot 29 through which a substantial portion of the gauge glass may be viewed.

Calibrated markings may be disposed along the edges of the slot 29 as desired.

The coupling 22 has a recess in the lower end into which the glass 28 extends, a passageway 31 extending upwardly therefrom through the upper end of the coupling and opening into the interior of the top section and a valved

passageway 32 extending upwardly from the recess 30 and then outwardly through the flange 24, opening into the annular space within the housing 1. The juncture of the gauge section with that next above is so arranged as to be below the packing gland 5 when the gauging assembly 17 is completely sheathed.

A valve seat is provided in the passageway 32 at the angular portion thereof.

The coupling 23 is of a generally annular form, the gauge glass 28 passing therethrough to seat on the member 26 which is provided with an inwardly extending flange 33 adapted to receive the end of the glass.

The intermediate section 20 is joined to the

bottom section 21 by means of a coupling 34 which as shown illustrates another form of coupling for the purpose indicated. In this instance the coupling is provided with a central passageway 35 in which is disposed a check valve 36 which rests upon perforated plate 58 when in its open position. Check valve 36 has been provided in the gauge 2 to increase the safety factor and prevent the escape of volatile material from the reservoir in event of damage to the upper part of the gauge 2.

The bottom section 21 has a circumferential groove 37 formed in its outer surface intermediate the ends, and an exteriorly threaded portion 38 spaced from the lower end. The lower end of the section 21 is machined or otherwise formed in such manner as to provide for a fluid tight seal with a disc of compressible material 39 disposed in the bottom of a closure 40 for the end of the casing. This closure comprises a cylindrical cap interiorly threaded intermediate of its length. A set screw 41 is threaded through the upper end of the cap so as to extend into the groove of the section 21. The cap has a port 42 near the bottom and a lug 43, exteriorly of its closed end, which is designed to fit into the groove 9 in the plug 8.

The top section 18 extends through the stuffing box member 11 and packing gland 44 and carries 30 at its outer end, and containable within the vapor cap 12, the gauge head 45. The head is provided with suitable openings for stemmed valves 46 and 47 which extend therethrough and with a passageway 48 opening through the head and preferably through a threaded nipple 49 thereon. The valve 46 is seated in the passageway 48 while the valve 47, extending downwardly through the top section 18 and through an opening in the coupling 22, is seated in the passageway 32. The 40 head 45 and stuffing box 11 may be provided for separable engagement in any suitable manner if so desired.

In Fig. 2 that portion of the housing 1 and assembly 17 including the packing gland 5 and 45 coupling 22, is shown in greater detail. A set screw 50 is shown as maintaining the tightness of the collared joint in the housing.

In Figs. 3 and 4, the relationship of the parts comprising the lower end of the gauge assembly 50 17 are shown with the valve device thereby provided in closed and open positions respectively. These figures show the use of multiple set screws 41 in order to prevent jamming of the cap 40.

In Fig. 5, the application of the invention to a 55 tank car is represented. In this case, the device extends up into the dome of the car and the collar 10 as shown in Fig. 1 may be omitted by threading the member 11 into the upper end of a suitable opening in the partition 51, and the upper 60 end of the housing 1 into the lower end of the same opening. Incident to the showing of this figure are the parts of the tank car including dome 52, cover 53, and drain valve 54. A level of liquid in the car body is shown as at 55.

65 In Fig. 6, the application of the invention to an underground storage tank is shown, in which the numeral 56 designates the tank and 57 the liquid level therein. In this instance, it will be noted, that the vent 16 has been located nearer 70 the lower end of the housing 1 so as to be disposed within the tank 56. Also, for the purpose of illustrating the operation of the gauge device, the gauge assembly 17 is shown in an unsheathed position, as when the liquid level is to be read 75 from the gauge glass 28 and calibrated slot 29.

Furthermore, as is indicated in this illustration, it is sometimes possible to omit the packing gland 5 as shown in Fig. 1, forming the housing 1 of one continuous tube, without affecting the operation of the device to any considerable extent. 5 However, when used in tanks under pressure, or from which considerable evaporation may take place, the packing gland 5 should always be provided so as to prevent loss and fire hazard should the valve head or packing gland be damaged in 10 any manner.

It should be evident from the foregoing description that this invention is particularly useful in 15 gauging liquid levels in containers in which access to the liquid is hazardous or difficult, when either very volatile liquids or liquids under pressure are involved or when the devices such as ordinarily used are in any way unsuitable. By means of the present invention it is possible to gauge the level of the liquid in a sealed container without 20 escape of vapors or liquid and without the atmosphere surrounding the container coming in contact with the liquid to be gauged.

There are two methods by which the gauging 25 operation may be carried out. The first is suitable for use under any pressure conditions existing in the tank, while the second is a convenient method of gauging liquid held under pressure somewhat greater than atmospheric.

By the first method, the gauging assembly is 30 turned in the housing while fully sheathed, in order to uncover the port 42 in the cap 40 which is normally closed by the end of the casing assembly 17. The lug 43 engages the groove 9 so as to maintain the cap 40 stationary while the 35 casing 17 is unthreaded until the set screws 41 stop further movement. The valve 47 is then withdrawn from its seat in the passageway 32, equalizing the pressure in the casing 17 with that of the container, through the vent 16. Allowing 40 a brief interval for such equalization, the valve 47 is again closed, the port 42 recovered by reverse movement of the casing and then the casing unsheathed from the housing, permitting the liquid 45 level in the tube 28 to be directly viewed through the slot 29 and the level read according to the calibration thereon.

According to the second method, the port 42 is 50 opened in the manner described above and the casing unsheathed for such length as is considered sufficient to clear the estimated liquid level. The valve 46 is then opened slightly and the casing lowered gradually until the liquid is discharged from the nipple 49, at which point it is known that the port 42 has reached the liquid level. 55 By noting the position of the calibration on the slot 29 with relation to a fixed point such as the upper end of the stuffing box member 11, the liquid level may be determined with a fair degree of accuracy. Although the loss of pressure and liquid through the passageway 48 will be very 60 small, this method is only satisfactory when exceedingly accurate readings, without loss of any sort, are not required or when only the approximate maximum upper level is required.

When the device is to be used as a sampling 65 device, it is only necessary, after opening the port 42 as described, to raise the casing a distance great enough to place a receptacle under the nipple 49 and open the valve 46, permitting 70 liquid to flow from the casing under pressure of the container contents. Obviously, sampling is most convenient when the container is under super-atmospheric pressure, although by applying sufficient suction at the nipple 49 a sam- 75

ple may be obtained when the container is under atmospheric or sub-atmospheric pressure.

Various changes and alternate arrangements may be made within the scope of the appended 5 claims, in which it is intended to claim all novelty inherent in the invention as broadly as the prior art permits.

I claim:

1. A gauge comprising a tubular casing, a valve 10 closure for the lower end of the casing, a valve head closing the upper end of the casing, a sight glass sealed in an intermediate portion of the passageway of the casing, the casing being slotted opposite the glass, the valve head having an 15 outlet, a valve controlling the outlet, the casing having a lateral outlet between the glass and the valve head, and a valve controlling the lateral outlet.

2. A gauge device according to claim 1 in 20 which the gauge is disposed in a tubular housing adapted to depend a predetermined distance from the roof of the container and having an inlet at its lower end, and interlocking means between the housing and the valve closure 25 whereby the closure is opened or closed by turning the casing.

3. An apparatus for gauging and sampling liquids in a closed container comprising a housing extending into the container and in free 30 communication with the contents thereof, a gauge casing, including a sight glass, extending into the housing from its upper end, a valved closure for the upper end of said casing and a valved closure for the lower end thereof, means 35 for operating the valve in the closure for the lower end, means for equalizing pressure within the casing with that existing in the housing and in the container, means for withdrawing liquid through the casing and means for maintaining 40 a fluid tight seal between the casing and housing while permitting partial withdrawal of the former from the latter.

4. An apparatus according to claim 3 in which the valved closure for the lower end of said 45 casing comprises a cap for said end having a lateral opening in the side wall in close proximity to the bottom of said cap, which opening is closable by the end of the casing threaded

into the cap, a projection on the bottom of the cap adapted to be held while the casing is rotated and a circumferential groove in the casing adjacent the end into which extend stops on the cap to limit movement of the casing with 5 relation thereto.

5. A device for collecting a sample of liquid from a reservoir, comprising a housing adapted to be suspended in said reservoir and being provided with ports to establish open fluid connection between the reservoir and the interior of the housing, a casing projecting into said housing and mounted for rotation relative thereto and a valve at the lower end of said casing normally sealing the interior of said casing from 15 the interior of said housing and operable by rotation relative to the casing, and means on the housing engageable with the valve whereby the valve is opened upon relative rotation of the casing with respect to the housing to establish 20 fluid connection between the interior of said casing and the interior of said housing.

6. A sampler according to claim 5 in which the lower end of the casing is open and the valve on said casing consists of a cylindrical 25 cap adapted to fit over the lower end of said casing and provided with an inlet port adjacent its closed end, interacting means on said cap and said casing for effecting relative longitudinal movement of the two upon relative rotation 30 thereof, and means carried by said cap and co-acting with said housing for holding said cap against rotation when said casing is rotated.

7. A sampler according to claim 5 in which the bottom wall of the housing is provided with 35 a socket of irregular shape, the lower end of the casing is open and the valve for said casing is a cylindrical cap, the closed end of which constitutes a seat for the open end of said casing, said cap being provided with an inlet port, interacting means on said cap and said casing for effecting relative longitudinal movement of the two upon relative rotation thereof, and a stud carried by said cap having a configuration conforming to that of said socket and adapted to 40 fit into said socket to hold said cap from rotation when the casing rotates.

HARRISON OTIS PARSONS.
